K. KIEFER

PULP WASHER

Filed May 8, 1923

UNITED STATES PATENT OFFICE.

KARL KIEFER, OF CINCINNATI, OHIO.

PULP WASHER.

Application filed May 8, 1923. Serial No. 637,541.

My invention relates to devices for washing pulp that has been used in filtering, removing the sediment and impurities so that the pulp may be used for filtering again. An object of my invention is to construct such a device in a simple manner for operation by power. A further object is to provide for the ready drainage of the impurities and sediment separated from the pulp in the operation of the machine, without loss of the pulp. A further object is to retain the pulp and at the same time prevent clogging of the drainage means by the pulp thus retained. Other objects will appear in the course of the ensuing description.

I accomplish these objects by the device illustrated, for example, in the accompanying drawing, in which—

Figure 1 is a general perspective view of the device; and

Fig. 2 is a partial vertical cross section on the plane of the line 2—2 of Fig. 1.

The tank 1 rests on a suitable support 2 having an extension supporting the motor 3 with its shaft extending toward the tank 1 and carrying a worm 4 meshing with a worm wheel 5 which, together with the motor shaft and worm, is journaled in a housing 6 on the support 2 next to the tank 1. On an extension of the worm wheel shaft, which is transverse to the tank 1, is a pulley 7 with a belt 8 passing around it. Arranged at intervals around the tank 1 near its circular upper rim, are brackets 9 in which are vertical studs on which rotate rollers 10 having grooved peripheries; and a rotor 11 is made of an angle bar bent into a ring with one leg of the angle at the bottom, projecting outwardly into grooves of the rollers 10. The belt 8 passes around the vertical part of the rotor 11, over idler sheaves 12 journaled in inclined brackets 13 on the side of the tank 1, which change its direction and keep it tight.

The rotor 11, thus rotated by the motor 3, has fixed on its inner upright surface at diametrically opposite locations the two yokes 14 depending from the rotor and carrying scrapers 15 trunnioned therein on vertical axes and having their edges, which may be of rubber or the like, passing against the screen 16, which is spaced inward from the wall of the tank all around having its

top and bottom edges, respectively, attached to annular flanges 16' and 16'' (Fig. 2) extending in from the wall of the tank, forming an annular conduit 17. The outflow through the screen 16 is conducted by the conduit 17 to the outlet head 18 opening out through the tank wall from the conduit 17 at one side and having a drain pipe 19 leading down from its bottom to any suitable drainage disposing means, not shown.

To cause circulation in the tank and agitate the contents thereof, the motor shaft is extended through the wall of the tank 1, with a suitable stuffing box 20 around the shaft, and just inside the tank this shaft carries a screw-bladed impeller 21, which drives the intermingled water and pulp forward and against the tank walls to be deflected thereby upward and outward to the screened outlet at the top, as indicated by the arrows in Fig. 1.

At the side of the tank 1 remote from the impeller 1 is a spout 22 closed by a suitable gate, for withdrawing the cleaned pulp.

In use, the tank is filled with water, and the pulp to be cleaned is placed therein and agitated, while a supply of fresh water is kept up as the water flows out through the screen 16 with the impurities washed from the pulp. The scrapers 15 not only keep the screen 16 from being clogged by the pulp fibers, but exert a rubbing action on the pulp against the screen, assisting in the thorough separation of the impurities from the pulp. As the effect of the agitation by the yokes, in conjunction with the impeller, is centrifugal, there is a constant outflow of fibers to the screen as fast as those are scraped away therefrom. As the operation, including clearing the screened outlet, is automatic, the operation may be kept up for an ample time to insure thorough cleansing of the pulp, without much attention from the operatives.

Modifications may occur, and I do not wish to be understood as being limited to the precise details herein shown and described, but what I claim as new and desire to secure by Letters Patent is:

1. In a pulp washer, a tank having an open top and a screened outlet at its side, mechanism positioned away from the center of the tank and passing against the screen of said outlet, an impeller inside said tank,

positioned away from the center of the tank and having operating means extending through the wall of the tank, and an operative connection from said impeller to said mechanism, outside said tank.

2. In a pulp washer, a tank having an open top and a screened outlet at its side, and mechanism positioned away from the center of the tank and a scraper driven by said mechanism and passing against the screen of said outlet.

3. In a pulp washer, a tank having an open top and an annular screened outlet away from the center of the tank, and mechanism comprising a rotatable ring extending around said outlet and a scraper carried around with said ring and passing against the screen of said outlet.

4. In a pulp washer, a tank having an upper annular screened outlet, and mechanism comprising a ring near said outlet and a scraper on said ring pressing against the

screen of said outlet, and rollers on said tank supporting said ring for rotation.

5. In a pulp washer, a tank having an upper screened outlet, and mechanism comprising a ring rotatably supported on said tank near said outlet and a scraper on said ring pressing against the screen of said outlet, and a belt passing around said ring for rotation thereof.

6. In a pulp washer, a tank having an upper annular screened outlet, motive means near the bottom of said tank, a ring rotatable near said outlet, a scraper carried by said ring pressing against the screen of said outlet, rollers on said tank supporting said ring, a belt passing around said ring and operatively related to said motive means, and sheaves on the side of said tank around which said belt passes from said ring to said motive means.

KARL KIEFER.
